17 Claims

ABSTRACT OF THE DISCLOSURE

A vehicle sign having a plurality of individual sign cards arranged in pairs and bound in a book-like assembly that can be opened at selected card to display different legends identifying goods carried by the vehicle. The sign book is mounted on a supporting member so that the sign book can be moved between a sign changing position and sign displaying position.

In the copending application of William J. Lowmaster entitled "Vehicular Sign," Ser. No. 690,236, filed Dec. 13, 1967, and assigned to the assignee of this application, there is disclosed a vehicular sign for indicating the character of goods carried by the vehicle wherein a pack of individual sign cards are stored in a sign carrier mounted on a supporting member. Signs are changed by moving the sign carrier to a sign changing position relative to the supporting member and then rearranging the individual cards to place the desired sign on top of the pack. When the sign carrier is pushed back into the supporting member, the sign cards are held in place by the sign carrier and the supporting member. Although this sign is useful for most applications, it is desirable to have different sign constructions available to meet the demand and choice of prospective purchasers. Also it is possible that a sign card may be lost accidentally or stolen.

Therefore, the object of the present invention is to provide an improved sign assembly for motor vehicles.

Other objects of the present invention are to provide a vehicle sign that facilitates rapid changing of the legends; that is free of fasteners that are difficult to manipulate during sign changing; that allows rapid changing of signs that are permanently but changeably incorporated in the sign assembly; that reduces the likelihood of theft and accidental loss of the sign cards; that is durable and rugged and yet of relatively low-cost construction; and that provides a wide selection of signs in a very compact assembly.

Another object of the present invention is to provide a sign assembly having interchangeable signs bound in a book-like assembly that is rugged and durable; that facilitates permanent mounting of the interchangeable sign on a vehicle or the like; and that facilitates rapid sign changing while minimizing the possibility of accidental loss of individual signs.

Other objects, features and advantages of the present invention will become apparent with the following description, the appended claims and the accompanying drawings in which:

FIG. 1 is a perspective view of a truck provided with a sign constructed according to one embodiment of the present invention;

FIG. 2 is an enlarged front plan view of the sign assembly of FIG. 1;

FIG. 3 is an enlarged rear plan view of the sign assembly;

FIG. 4 is an enlarged horizontal sectional view taken on line 4—4 of FIG. 2 and also illustrating a portion of the truck body;

2

FIG. 5 is an exploded view of the sign assembly of FIGS. 2-4;

FIG. 6 is a perspective view illustrating an alternative embodiment of a sign assembly which is shown in an open position;

FIG. 7 is a perspective view of the sign of FIG. 6 in a closed position;

FIG. 8 is an enlarged fragmentary vertical section taken along the line 8—8 in FIG. 6; and

FIG. 9 is an enlarged fragmentary horizontal section taken along line 9—9 of FIG. 7.

In FIG. 1 there is illustrated a sign assembly 10 of the present invention mounted on the trailer 12 of a truck 14. Preferably more than one sign is carried on truck 14, commonly at other conspicuous locations on the trailer 12, such as the front, the rear and both sides of the trailer as illustrated by a second sign assembly 16. Conspicuous display of such a sign identifying the cargo carried by truck 14 is required by law for certain goods. Trailer 12 is illustrated as having vertical corrugations 18 and the width of sign 10 is selected so that the sign may be mounted flat against the body of the trailer 12 between adjacent corrugations 18.

Referring more particularly to FIGS. 2-5, the sign assembly 10 generally comprises a supporting member 20 fixedly mounted on the body of trailer 12. A sign carrier 22 is mounted on support 20 for vertical movement relative thereto from a closed, sign-displaying position illustrated in full lines in FIGS. 2 and 3 to an open, sign-changing position illustrated in dashed lines in FIGS. 2 and 3. Mounted on the sign carrier 22 are two book-like sign assemblies, an upper sign book assembly 24 and a lower sign book assembly 26, each of which comprises a plurality of individual sign cards bound together so that a particular sign can be selected when carrier 22 is in its raised position.

More particularly, the supporting member 20 comprises a generally rectangular backing panel 30 that is mounted directly on the surface of trailer 12 by means of suitable fasteners such as rivets 32. In the preferred embodiment, supporting member 20 is made of sheet metal, such as 32 gauge primed aluminum, although other materials may also be used. Along each vertically extending side edge of the backing panel 30 is a forwardly extending flange 34, 36, respectively. Each flange 34, 36 has a return bent tab 37, 38, respectively, that extends laterally inwardly parallel to the backing panel 30 and overlying the carrier 22. Each flange 34, 36 and its tab 37, 38 extends vertically slightly more than one-half of the height of the backing panel and on the order of two-thirds of the height of the backing panel in the preferred embodiment to overlie the lower portion of assembly 24 when carrier 22 is in its lowered position. Backing panel 30 also has an integral horizontal flange 40 along its lower-most edge that serves as a support and stop for the carrier 22. Two integral ribs 42 are spaced apart laterally of the backing panel 30 and extend substantially the full height of the backing panel from just above the lower-most edge thereof to the upper edge. Each of the ribs 42 has a generally flat front face 44 and a longitudinal slot 46. Ribs 42 and slots 46 serve to slidably support carrier 22 for vertical movement on the supporting member 20.

Carrier 22 comprises a flat panel 48 formed along its top edge with a forwardly projecting top flange 50 along each side edge with a forwardly projecting side flange 52. Carrier 22 is also preferably made of sheet metal, although other similar materials, such as plastic, that lend themselves to fabrication of the desired shape may also be used. Carrier 22 is slidably fastened on member 20 by two rivets 56 which extend rearwardly through slots 46 and have a washer 58 thereon at the rear side of ribs

42. Rivets 56 are disposed near the lower edge of carrier 22 to bottom in the lower ends of slots 46 when carrier 22 bottoms on flange 40. Rivets 56 are loose so that carrier 22 slides freely relative to member 20. The height of the ribs 42, the lateral flanges 52, and the tabs 37, 38 are selected so that the front edge of the flange 52 5 sildably engages the underside of the tabs 37, 38.

Each of the book-like sign assemblies 24, 26 comprises eight individual cards 60 whose height is approximately one-half the height of the carrier 22 and whose width is also approximately one-half the width of the carrier 22. Cards 60 are made of sheet metal, such as 16 gauge aluminum in the preferred embodiment, although other materials may also be used. The individual cards 60 in each of the assemblies 24, 26 are hingedly connected to carrier 22 by a binder 62 which generally comprises a base plate 64 and four integral hinge tabs, two tabs 66 for the upper sign assembly 24 and two tabs 68 for the lower sign assembly 26. The binder 62 is fastened on carrier 22 by rivets 70 with plate 64 disposed at the rear side of carrier 22. Tabs 66, 68 have a semi-circular configuration and project forwardly through generally rectangular apertures, two apertures 72 for the upper assembly 24 and two apertures 74 for the lower assembly 26, through narrow slots 76 in cards 60 of the upper assembly 24 and back through apertures 72. A flat tab portion 78 at the free end of each tab 66 abuts the rear face of panel 30 to retain the tabs tightly in place. Similarly the lower tabs 68 pass through slots in the cards 60 in the lower assembly 26 and are retained in place by end tab portions 80. Midway between the top and the bottom of the carrier 22 are a pair of struck out tabs 84 which project forwardly underneath the lower edge of the cards in the top assembly 24 to assist supporting the cards in a straight horizontal line.

The card assemblies 24, 26 are assembled in place on carrier 22 by inserting the tabs 66, 68 through the corresponding apertures 72, 74 with the base plate 64 disposed generally perpendicular to the back surface of the panel 48. The cards 60 are then threaded on tabs 66, 68. The tabs 66, 68 are then pivoted downwardly in a generally counterclockwise direction, as viewed in FIG. 4, and moved to an extreme position toward the right, as viewed in FIG. 4, so that the end tab portions 78, 80 can pass downwardly and rearwardly through apertures 72, 74. The binder 62 is then moved toward the left as viewed in FIG. 4 so that the end tab portions 78, 80 are disposed beneath the backing panel 30, adjacent the apertures 72, 74. Base plate 64 is then riveted to the carrier 22. In the preferred embodiment, the binder 62 is formed of a relatively stiff sheet metal and the width of apertures 72, 74 is such that the above assembly operation can be performed without compressing the tabs 66, 68. However, by using a more resilient sheet metal or other suitable materials, such as plastics, the width of the apertures 72, 74 can be such that the tabs 66, 68 must be radially compressed in order for the tabs to pass back downwardly through the apertures after the cards 60 are assembled thereon.

With the book-like assemblies 24, 26 mounted on the carrier 22 as described hereinabove, when the carrier is in a closed position with selected pairs of cards lying flat and disposed side by side as shown in full lines in FIGS. 2 and 3, the tabs 37, 38 overlie the laterally outward edges of the cards 60 in both the upper assembly 24 and the lower assembly 26 to hold the cards in place displaying a selected sign such as the "Flammable Gas" sign shown in FIG. 2. When it is desired to change the sign being displayed, the carrier 22 is raised with rivets 56 moving upwardly in slots 46 until the rivets reach the upper ends of the slots. At the upper travel limit of carrier 22, the lower-most edges of the cards in the lower assembly 26 clear the top edge of the flanges 34, 36 and tabs 37, 38, as illustrated in dashed lines in FIGS. 2 and 3. The individual cards may then be turned on the

tabs 66, 68 to select different signs. After the sign has been changed, the carrier is then moved to its lower position with the cards 60 being again retained in place by the flanges 34, 36. A suitable lock (not shown) may be provided in the assembly 10 to lock the carrier 22 in the closed position.

In the preferred embodiment, the upper sign assembly 24 and the lower sign assembly 26 have duplicate sets of cards. Side-by-side faces of adjacent cards are printed with a legend such as "Flam" on the back of one card and "Mable" on the front of the adjacent card as shown in FIG. 2. The upper and lower sign assemblies 24, 26 facilitate the simultaneous display of two different legends, such as "Flammable" and "Gas" or "Compressed" and "Gas," one by each of the assemblies 24, 26. Each of the sign assemblies includes at least one blank, unprinted set of cards so that a single legend such as "Poison" may be displayed on the other assembly. One legend, or the "blank" legend, may be provided on the left-hand side, as viewed in FIG. 2, of the back panel 48 and the front of the top one of the cards 60 for display when the cards are all turned to the right-hand position and another legend may be provided on the right-hand side of panel 48 and the back of the back one of the cards 60 for display when the cards are all turned to the left-hand position. Where it is desirable to provide a thinner sign assembly, the cards 60 in the sign assembly 24 may carry legends different from those on the cards in the lower sign assembly 26.

The sign construction disclosed hereinabove may be fabricated simply and economically and requires very few parts and no separate fasteners. A wide variety of legends may be displayed and the legends can be readily changed. It will be apparent that one of the assemblies 24, 26 could be eliminated providing a corresponding reduction in the height of the sign assembly, but the dual sign assembly, using the upper assembly 24 and the lower assembly 26, is preferred and permits a large number of signs to be displayed in a thin package. Permanent attachment of the cards 60 to the carrier 22, of the carrier to the supporting member 20, and of the member 20 to the truck 14 deters theft and prevents accidental loss of the sign cards.

Referring to the embodiment illustrated in FIG. 6, a sign 90 comprises a generally rectangular support member 91, an upper book-like sign assembly 92 and a lower book-like sign assembly 93. The support member 91 comprises a flat, generally rectangular back panel 94 formed with an integral horizontal flange 96 extending forwardly from along the top edge of panel 94 and a lower horizontal flange 98 projecting forwardly from the lower edge of panel 94. Along each side of panel 94 is a forwardly projecting vertical side flange 100. Each flange 100 has a laterally inwardly projecting tab 104 that extends parallel to and overlies the laterally outermost edges of the back panel 94. At each end of the top flange 96 is a horizontal extending slot 97 having its laterally outer end disposed behind the corresponding side tab 104. Bottom flange 98 also has a slot 99 disposed at each end behind tabs 104. The supporting member 91 is made of sheet metal in the preferred embodiment, although it is to be understood that other material suitable for fabrication in the above described member can also be used.

The upper sign assembly 92 comprises a plurality of cards 106 which are bound together and to the upper portion of a pair of card carrier panels 108, 110, respectively. Cards 106 are approximately one-half the width of the back panel 94 and have a height that is slightly greater than one-half the height of the back panel. The carrier panels 108, 110 extend substantially the full height of the back panel 94 between the top flange 96 and the bottom flange 98. The width of panels 108, 110 is approximately one-half the width of the back panel 94. Cards 106 are bound on panels 108, 110 by means of closed, ring-shaped bands 112 that pass through all of the cards

106 and panels 108, 110 so that the cards 106 are permanently and hingedly attached to panels 108, 110. Similarly, the lower card assembly 93 comprises a plurality of cards 116 mounted on the lower portion of panels 108, 110 by means of closed ring-shaped bands 118. The width of cards 116 is again approximately one-half the full width of panel 94 and the height is slightly less than one-half the height of the panel 94. Although the cards 106, 116 have been described as having different heights, which construction may be required to display certain legends, it is to be understood that the cards 106, 116 might have substantially equal heights, approximately one-half the height of the back panel 94, as with the cards 60 described hereinabove in connection with FIGS. 2-5. The cards 106, 116 are made of stiff sheet metal in the preferred embodiment.

The laterally outer edge of each carrier panel 108, 110 has an integral tubular guide 122 formed by rolling the edge of the panel rearwardly and then abutting the edge against the rear face of the panel. Guides 122 extend the full height of panels 108, 110. Each panel 108, 110 is movably supported on member 91 by a pin 124 that extends downwardly through slot 97 in flange 96, through guide 122 and then through slot 99 in the lower flange 98. Each end of each pin 124 is formed with a suitable head as at 130 so that the pin is slidably fastened to the supporting member 91. A clasp 134 fastened on the back panel 94 has a snap-over finger 136 yielding movable from an open position shown in FIG. 6 to a closed position shown in FIG. 7.

With the sign 90 having the construction described hereinabove, when pins 124 are moved to their extreme laterally outer positions in slots 97, 98 with panels 108, 110 lying flat parallel to back panel 94, the laterally outer edges of cards 106, 116 are disposed beneath the side tabs 104. Finger 136 is then snapped forwardly and downwardly against the front face of the exposed cards to retain the card assemblies 92, 93 in a flat condition with tabs 104 retaining the laterally outer edges of the cards 106, 116 in place. When it is desired to change the sign, finger 135 is opened to the raised position illustrated in FIG. 6 and the card assemblies 92, 93 are moved forwardly to their open, sign-changing position by moving the inner edges of the panels 108, 110 forwardly away from the back panel 94. As the center of the sign assemblies 92, 93 hinges away from the back panel 94, pins 124 slide laterally inwardly in slots 97, 98 and the outer edges of cards 106, 116 move out from under the flanges 104 so that the cards are free to be turned to a desired sign.

The sign 90 described hereinabove may also be fabricated simply and economically and it facilitates the display for a wide variety of signs that can be changed readily. As with the sign 10 described hereinabove in connection with FIGS. 2-5, the signs printed on cards 106 of the assembly 92 may be the same as those printed on the cards 116 of the assembly 93 or different signs may be printed on the cards in assembly 92 from those printed on the cards 116 of the assembly 93, depending upon the particular application involved. Although a particular clasp 134 has been disclosed to hold the assemblies 92, 93 in place, other types of fasteners as well as other arrangements will be readily apparent. For example, a releasable catch to hold each pin 124 in its extreme laterally outward position (FIG. 7) could be used to hold the sign 90 in the closed position illustrated in FIG. 7.

The sign assemblies have been described hereinabove for purposes of illustration and are not intended to indicate limits of the present invention, the scope of which is defined in the following claims.

What is claimed is:

1. A sign for motor vehicles or the like comprising a supporting member adapted to be mounted on the vehicle and having a backing panel, first and second flanges integral with said backing panel and disposed, respec-

tively, at opposite vertically extending edges thereof, said flanges extending forwardly from said panel and having tab portion projecting laterally inwardly and overlying said backing panel, a plurality of individual indicia bearing cards each having a width on the order of one-half the lateral spacing between said first and second flanges, hinge means binding said cards together in a book-like assembly so that selected pairs of cards may be disposed side by side, and card carrying means supporting said card assembly on said supporting member so that cards may be turned in a direction from one side to the other side of said supporting member, said card carrying means being movably mounted on said supporting member and cooperating with said lateral tab portions so that in one position of said card carrying means said lateral tab portions overlie laterally outer edges of said cards to retain a selected pair of cards side by side and so that when said card carrying means is moved to a second position said card edges move out from underneath said lateral tab portions and are freed from retention by said lateral tab portions.

2. The sign set forth in claim 1 wherein said card carrying means comprises carrier panel means, said tab portions on said lateral flanges form a guide and said carrier panel means is vertically slidable in said guide so that when selected cards are disposed side by side and said carrier panel means is disposed in a lowered position in said guide said tab portions overlie laterally outermost edges of said cards and when said carrier panel means is raised lowermost portions of said edges of said cards are disposed above said tab portions.

3. The sign set forth in claim 2 wherein said supporting member has a third flange integral with said backing panel at a lower horizontal edge thereof and projecting forwardly of said backing panel, said third flange having a tab portion projecting upwardly and overlying said backing panel so that when said card carrying means is disposed in said lowered position lowermost edges of said cards are retained behind said tab portion of said third flange.

4. The sign set forth in claim 2 wherein said supporting member has at least one slot therein extending in a vertical direction parallel to the direction of travel of said carrier panel means in said guide, and follower means movable in said slot and operatively connected to said supporting member and said carrier panel means so that the carrier panel means is vertically slidable with said follower means moving in said slot and retaining said carrier panel means interconnected with said supporting member.

5. The sign set forth in claim 2 wherein said supporting member has a pair of spaced-apart, vertically extending ribs projecting forwardly of said backing panel, an elongated slot in each of said ribs extending longitudinally of each rib in a direction parallel to the direction of travel of said carrier panel means in said guide and a pin follower disposed in each of said slots and operatively connected to said supporting member and said carrier panel means so that said carrier panel means is slideable on said ribs with said pins moving in said slots and retaining said carrier panel means on said supporting member.

6. The sign set forth in claim 1 wherein said hinge means comprises an elongated base plate and a plurality of arcuate tabs spaced apart longitudinally along said base plate and integral therewith, a plurality of apertures in said backing panel, said base plate being disposed at a rear side of said backing panel and being mounted on said backing panel with said hinge tabs projecting forwardly through said apertures and passing through each of said cards, and wherein each hinge tab has a generally flat portion at the free end thereof abutting said rear side of said backing panel.

7. The sign set forth in claim 6 wherein the dimension of each aperture in a direction laterally of said backing

panel is greater than the straight line dimension of said hinge tab from its base to its free end.

8. The sign set forth in claim 6 wherein a second book-like assembly is supported on said card carrying means below said first-mentioned book-like assembly and aligned end to end therewith, said second book-like assembly comprises a second plurality of cards hingedly bound together so that selected cards may be disposed side by side and turned in a direction from one side to the other of said supporting member, and wherein said second book-like assembly includes hinge means having a base plate portion integral with said base plate of said first-mentioned hinge means.

9. The sign set forth in claim 1 wherein a second book-like assembly is supported on said card carrying means below said first-mentioned book-like assembly and aligned end to end therewith, said second book-like assembly comprising a second plurality of cards hingedly bound together so that selected cards may be disposed side by side and turned in a direction from one side to the other side of said supporting member, and wherein said tab portions are disposed to retain selected pairs of cards side by side in said second assembly when said card carrying means is disposed in said one position.

10. The sign set forth in claim 1 wherein all of said cards have substantially the same dimensions, each of said cards having indicia thereon correlated to the indicia on an adjacent card in said book-like assembly so that when a selected pair of cards are disposed side by side the indicia thereon present a predetermined legend.

11. The sign set forth in claim 1 wherein said card carrying means comprises a pair of card carrying panels disposed side by side and hingedly connected together by said hinge means to support said cards on said card carrying panels, and means interconnecting each of said card carrying panels with said supporting member for sliding movement of laterally outer edges of said card carrying panels in a direction laterally of said supporting member so that when selected cards are disposed side by side on said card carrying panels and said card carrying panels are moved to a laterally outermost position said tab portions overlie laterally outermost edges of said cards and when said card carrying panels are moved laterally inwardly said edges of said cards move laterally inwardly to a position free of retention of said tab portions.

12. The sign set forth in claim 11 wherein said means interconnecting said card carrying panels and said supporting member for sliding movement comprises at least one elongated slot at each side of said supporting member extending longitudinally in a direction laterally of said supporting member, and follower means on each card carrying panel movable in a respective slot and operatively connected to said supporting member so that said card carrying panels are slidable in a direction laterally of said supporting member with said follower means moving laterally inwardly along said slots and retaining said card carrying panels on said supporting member.

13. The sign set forth in claim 11 wherein said supporting member has a third flange integral with said backing panel at a lower horizontal edge thereof and projecting forwardly of said backing panel, a fourth flange integral with said backing panel along the upper horizontal edge thereof and projecting forwardly of said backing panel, an elongated slot at each end of said third flange adjacent a respective one of said lateral flanges, an elongated slot at each end of said fourth flange adjacent a respective one of said lateral flanges, each of said slots extending longitudinally in a direction laterally inwardly from its adjacent lateral flange, and a pin follower disposed in each of said slots and engaging a laterally outer portion of an adjacent card carrying panel to slidably retain said card carrying panels on said supporting member.

14. The sign set forth in claim 11 wherein said hinge means moves in a direction forwardly and outwardly of said backing panel in response to lateral movement of said card carrying panels and wherein said sign further comprises a retaining member mounted on said supporting member and releasably engageable with said book-like assembly to restrain forward motion of said hinge means when a selected pair of cards are disposed side by side with the laterally outermost edges of said selected cards retained by said tab portions.

15. The sign set forth in claim 11 wherein a second book-like assembly is supported on said card carrying panels below said first-mentioned book-like assembly and aligned end to end therewith, said second book-like assembly comprising a second plurality of cards hingedly bound together so that selected cards in a pair may be disposed side by side and turned in a direction from one side to the other side of said supporting member.

16. A sign for a motor vehicle or the like comprising a supporting member having a backing panel adapted to be fastened on the vehicle, said supporting member having first and second integral outwardly extending flanges at opposite vertically extending side edges of said backing panel, first and second tab means formed integrally with said first and second flanges, respectively, and extending laterally inwardly of said backing panel and substantially parallel thereto to form a guide, a sign carrier slidably supported for vertical movement in said guide, the uppermost edge of said supporting member being substantially free of flanges to permit said carrier to be moved upwardly relative to said supporting member, a third integral outwardly extending flange at the lowermost horizontal edge of said backing panel to limit downward movement of said carrier, a first plurality of sign cards, hinge means binding said cards together in a first book-like assembly, said book-like assembly being fastened to said carrier substantially midway between said lateral flanges, some of said cards being disposed at one side of said hinge means with the laterally outer edges thereof disposed behind said tab means on one of said lateral flanges, the remaining cards being disposed on the other side of said hinge means with the laterally outer edges thereof disposed beneath said tab means on the other of said lateral flanges, a second plurality of sign cards, and second hinge means binding said second cards together in a second book-like assembly, said second book-like assembly being fastened to said carrier substantially midway between said lateral flanges and below said first book-like assembly, some of said cards in said second book-like assembly being disposed at one side of said hinge means with the laterally outer edges thereof disposed behind said tab means on one of said lateral flanges, and the remaining cards in said second book-like assembly being disposed at the other side of said hinge means with the laterally outer edges thereof disposed beneath said tab means on the other of said lateral flanges.

17. A sign for a motor vehicle or the like comprising a supporting member having a backing panel adapted to be fastened on the vehicle, said supporting member having first and second integral outwardly extending flanges at opposite vertically extending side edges of said backing panel, first and second tab means formed integrally with said first and second flanges, respectively, and extending laterally inwardly of said backing panel and substantially parallel thereto, a third flange at the lowermost horizontally extending edge of said backing panel and extending forwardly of said backing panel, an elongated slot at each lateral end of said third flange adjacent a respective one of said side flanges, a fourth flange at the uppermost horizontally extending edge of said backing panel and projecting forwardly of said backing panel, an elongated slot at each lateral end of said fourth flange adjacent a respective one of said side flanges, said slots extending longitudinally in a direction laterally inwardly from said side flanges, a pair of card carrying panels disposed

side by side and hingedly connected together at their adjacent side edges, said card carrying panels extending vertically between said third and said fourth flanges and laterally outwardly to said slots, a pin disposed in each of said slots and engaged with an adjacent card carrying panel, a first plurality of sign cards hingedly bound together in a first book-like assembly and fastened on an upper portion of said card panels substantially midway between said lateral flanges, some of said cards being disposed at one side of said first assembly hinge with the laterally outer edges thereof disposed behind said tab means on one of said lateral flanges, the remaining cards being disposed at the other side of said first assembly hinge with the laterally outer edges thereof disposed beneath said tab means on the other of said lateral flanges.

hinge with the laterally outer edges thereof disposed behind said tab means on one of said lateral flanges, and the remaining second cards being disposed at the other side of said second assembly hinge with the laterally outer edges thereof disposed beneath said tab means on the other of said lateral flanges.
